Primary Examiner — Kevin K Rudzinski*Assistant Examiner* — Amber J Rabie(74) Attorney, Agent, or Firm — Banner & Witcoff, Ltd.(57) CLAIM

The ornamental design for a shirt, as shown and described.

DESCRIPTION

FIG. 1 is a front perspective view of a shirt showing my new design;

FIG. 2 is a front view thereof;

FIG. 3 is a right side view thereof;

FIG. 4 is a left side view thereof; and,

FIG. 5 is a rear view thereof.

The broken lines depicting the remainder of the shirt form no part of the claimed design.

1 Claim, 5 Drawing Sheets(56)
